SHINGLE

Herbert Abraham, New York, N. Y., assignor to
 The Ruberoid Co., New York, N. Y., a corporation of New Jersey

Application November 21, 1951, Serial No. 257,553

5 Claims. (Cl. 108—7)

1

This invention relates to a shingle and more particularly a prepared roofing or asphalt shingle of the type that may be laid in courses with other like shingles to effect either single or double coverage.

By the term "single coverage" is meant a covering having only one thickness of roofing material at certain portions of the roof surface, and by the term "double coverage" is meant a covering of at least two thicknesses of material at all portions of the surface.

One object of the invention is to provide a shingle that may be laid for either single or double coverage with a minimum of material.

A further object of the invention is to provide a shingle of the character described that may be cut from a web or sheet of roofing material with no waste.

A still further object of the invention is to provide a shingle that is self-aligning when laid either for single or double coverage.

Another object is to provide a shingle that forms exposure patterns of attractive appearance when laid.

Still another object is to provide shingles that may be applied, with only two fastening elements for each shingle so arranged that each shingle of the several courses is held by said fasteners at four points in the case where the shingles are laid for double coverage and at six points where they are laid for single coverage.

In the accompanying drawings illustrating the invention:

Figure 1 is a plan view of one form of the shingle;

Figure 2 is a plan view of a modified form of the shingle;

Figure 3 is a plan view of a fragment of a sheet of roofing material showing the manner in which the shingles are cut without waste;

Figure 4 is a plan view of an assembly of several shingles laid in courses to effect a covering of single coverage;

Figure 5 is a similar plan view of the shingles laid to effect a covering of double coverage; and,

Figure 6 is a sectional view taken on the line 6—6 of Figure 4.

In my co-pending application Serial No. 251,589, I have shown and described an interlocking shingle that may be laid to effect either single or double coverage. The present invention relates specifically to shingles of the non-interlocking type in which the butts must be held down by fasteners.

The preferred form of shingle illustrated in

2

Fig. 1 comprises a rectangular head portion 10 and a shank portion 11. The head is defined by parallel vertical side edges 12—12, and horizontal top edge 13 and bottom edges 14—14. The shank is defined by vertical side edges 15—15 and 16—16, all of the same height, connected together by inclined edges 17—17, and it has a straight bottom or butt edge 18. The lower end of the edges 15 form corners 19 with the adjoining edges, which in this form are the edges 17. These corners 19 serve as guides for laying the shingles to effect double-coverage, as will hereinafter be described.

The two edges 14 of the head portion are each equal in length to one-half the length of the butt edge 18 of the shank portion. The overall height *c* of the shingle is equal to twice the height *a* of the shank portion plus the amount of headlap *b*, which latter is the minimum permissible safe headlap when the shingles are laid for single coverage. The distance *b* in the preferred form of my shingle is two inches. In other words the total height of the shingle is $c=2a+b$. The height *d* of the edges 15 and 16 is defined by the formula $d=a-\frac{1}{2}c$, while the height *e* of the inclined edge 17, measured vertically, is defined by the formula $e=a-2d$.

The overall dimensions of the preferred form of the shingle are 24" by 24", the height of the head portion being 13" and the height of the shank being 11". With shingles of these dimensions and form, the total area of material per shingle is 444 square inches. When the shingles are laid as in Fig. 4 to effect single coverage the number of shingles required per square is about 54, and the amount of material necessary to cover a square is about 169½ square feet. When the shingles are laid to effect double coverage, as in Fig. 5, the number of shingles applied per square is 75, and the amount of material required to cover a square is about 231¼ square feet. As will appear from these figures my improved shingle is extremely economical in the amount of material used to make the shingle and also to cover a square of roof surface when laid for either single or double coverage.

The shingles may be cut across the width of a sheet or web roofing material 20 without any waste in the manner shown in Fig. 3 of the drawings. Two rows or courses of shingles, each shingle having an overall height of 24" may be so cut from a sheet or web of 37" width. In any case the width of web required to cut two rows of shingles without waste regardless of the specific dimensions of the shingles may be obtained

from the following formula: $x=3a+2b$, where x indicates the width of the web and a and b indicate the dimensions hereinabove described.

When the shingles are laid, either for single or double coverage, the side edges 12 of adjacent shingles of each course contact each other, with the upper edges 13 of said shingles in horizontal alignment, and thus the shingles are self-aligning. In laying to effect single coverage, as in Fig. 4, the butt edge 18 of each overlying shingle is laid to register with the edges 14-14 of the two adjacent shingles of the underlying course, and accordingly it will be seen that the edges 14 provide guides for easily and properly applying the shingles to form a roof of single-coverage. In laying the shingles for double-coverage, as in Fig. 5, the butt 18 of each overlying shingle lines up with the corners 19 of the two adjacent shingles of the underlying course, thus said corners provide guides for properly applying the shingles to effect double-coverage.

The shingles may be secured by clinchers or fasteners such as described in my patent No. 2,570,626 of October 9, 1951, although other suitable form of fasteners may be used. As shown in Fig. 6, the lower shank or nail portion 21 of each fastener is driven through the underlying shingle or shingles in position that its upper shank or clincher portion 22 can penetrate through and be bent down upon a corner of the butt of the overlying shingle. On referring to Figs. 4 and 5 it will be seen that two clinchers 22 are used for each shingle, one in each corner of the butt. In the case of shingles laid for single-coverage, when so fastened each shingle will be held at four points, and when laid for double-coverage each shingle will be held at six points. This arises from the fact that the fasteners, as applied, secure not only the upper shingle but also the lower ones through which the nail portions of the fasteners are driven.

The modified form of shingle shown in Fig. 2 has the same relationship and proportions of parts as the preferred form previously described, and it is applied to a roof in the same manner to effect either single or double coverage. The modified form differs only in that the shank portion 11 has vertical side edge portions 23 instead of inclined edges 17, the edge portions 23 being connected to the edges 15 and 16, respectively, by horizontal edges 24 and 25 of equal lengths. In this form the lower end of edges 15 form corners 19 with the adjoining edges 24, which corners provide guides for the double-coverage application of the shingles in the same manner as described in connection with the form of shingle shown in Fig. 1.

What I claim is:

1. A self-aligning shingle of the non-interlocking type, adapted to be laid in courses with other like shingles to effect single or double-coverage, said shingle comprising a rectangular head having parallel vertical sides and horizontal top and bottom edges, and a shank extending downward

from the bottom of the head and spaced inward from each side thereof a distance equal to one-half the length of the lower end or butt of the shank, said shank having upper and lower vertical side portions of equal height connected by intermediate side portions, the overall height of the shingle being equal to twice the height of the shank plus the vertical extent that the head is to be lapped by an overlying shingle for single-coverage.

2. A self-aligning shingle of the non-interlocking type, adapted to be laid in courses with other like shingles to effect single or double-coverage, said shingle comprising a rectangular head having parallel vertical sides and horizontal top and bottom edges, and a shank extending downward from the bottom of the head and spaced inward from each side thereof a distance equal to one-half the length of the lower end or butt of the shank, said shank having upper and lower vertical side portions of equal height connected by downwardly converging side portions, the overall height of the shingle being equal to twice the height of the shank plus the vertical extent that the head is to be lapped by an overlying shingle for single-coverage.

3. A self-aligning shingle of the non-interlocking type, adapted to be laid with other like shingles to effect single or double-coverage, said shingle comprising a rectangular head having parallel vertical sides and horizontal top and bottom edges, a shank extending downward from the bottom of the head and spaced inward from each side thereof a distance equal to one-half the length of the lower end or butt of the shank, said shank having upper and lower vertical side portions of equal height, intermediate vertical side portions spaced equally from said vertical portions and connected therewith by horizontal edges, the overall height of the shingle being equal to twice the height of the shank plus the vertical extent that the head is to be lapped by an overlying shingle for single-coverage.

4. A shingle as in claim 1, wherein the portions of the bottom edge of the head that extend outward horizontally beyond the sides of the shank provide guides for positioning the lower end or butt of overlying shingles to effect single-coverage when the shingle is laid in courses with like shingles.

5. A shingle as in claim 1, wherein the corners at the lower ends of the upper vertical side edges of the shank provide guides for positioning the lower end or butt of overlying shingles to effect double-coverage when the shingle is laid in courses with like shingle.

HERBERT ABRAHAM.
